UNITED STATES PATENT OFFICE.

JOHN C. F. RIPLEY, OF WHEELING, WEST VIRGINIA.

COMBINED CAR AND AIR-BRAKE COUPLING.

SPECIFICATION forming part of Letters Patent No. 451,654, dated May 5, 1891.

Application filed December 4, 1890. Serial No. 373,526. (No model.)

To all whom it may concern:

Be it known that I, JOHN C. F. RIPLEY, a citizen of the United States, residing at Wheeling, in the county of Ohio and State of West Virginia, have invented certain new and useful Improvements in Combined Car-Couplers and Air-Brakes; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention consists in a new and improved combined automatic car and air-brake coupling in which the cars will be automatically coupled together, and can be coupled from either the top or sides of the cars without any necessity for going between them, thus preventing the many serious and fatal accidents which occur with the common link-and-pin coupler generally used, and in which the air-valves at the ends of the cars are automatically closed when the cars are uncoupled and automatically opened when the cars are coupled together, and my invention will be hereinafter fully described and claimed.

30 Referring to the accompanying drawings, Figure 1 is a longitudinal horizontal sectional view of my invention, showing the cars uncoupled. Fig. 2 is a side view of the same. Fig. 3 is a longitudinal horizontal sectional view of the invention, showing the cars coupled together. Fig. 4 shows the invention as applied to the engine and cab. Fig. 5 illustrates the uncoupling-levers. Fig. 6 is a side view of the coupling device, showing the 35 bumper-block arranged on the same. Fig. 7 is a horizontal sectional view showing the device which is used when two corresponding ends of the coupler come together. Fig. 8 is an end view of one of the castings. Fig. 9 is a detail view showing how the plate 29 is clamped on the end of the part 6.

40 The same numerals of reference indicate corresponding parts in all the figures.

45 Referring to the several parts by their designating-numerals, beneath each end of a car

are mounted in bearings 1 two parallel movable metal tubes 2. To the flanged outer ends of one pair of tubes is bolted a casting 3, which is formed with two longitudinal bores or openings 4 4, communicating at their inner ends with the open ends of the tubes and contracting or diminishing in size toward their outer ends. This casting is formed with 55 the inclined heads or wings 5 at its opposite sides. The flanged outer ends of the tubes at the other end of the car have bolted to them a casting 6, which is formed with longitudinal bores or openings 7 7, which communicate at their inner ends with the tubes and contract in size toward their outer ends. The outer end of the casting 3 is formed, as shown in Fig. 8, with a deep central recess 8, while the outer end of the casting 6 is formed 60 with the central projection 9, adapted to fit in the central recess 8 of the other casting and the side projections 10 10, which fit on each side of the outer end of said casting.

65 On the casting 6 is secured the cross-piece 75 11, on the ends of which are pivoted the clamps or hooks 12 12. The springs 13, arranged on the inner side of the rear ends of the pivoted clamps 12, keep their outer hooked ends pressed toward each other. It will now 70 be seen that when two cars provided with my invention approach each other, as shown in Fig. 1, the outer ends of the clamps 12 will engage over the wings 5, and the cars thus be automatically coupled together. The springs 85 13 will hold the clamps 12 in this engaged position. Between the inner ends of the tubes 2 are firmly secured the outer ends of drawbolts 14, each of which passes through the bearing 15 and has a spiral spring 16 encircling it between the said bearing and a fixed washer 17. By means of these bolts the cars are drawn through the coupling devices when the cars are coupled together, and when the cars move the spring 16 will give and 90 again press the bolts outward, acting as spring-bumpers. The inner ends of the clamps 12 are connected by chains 18 18 with the lower end of the upright shaft 19, having a hand-wheel at its upper end by turning which from 95 the top of the car the outer ends of the clamps can be separated, and the cars thus uncoupled.

100 20 indicates the horizontal shaft mounted

at the end of the car and having a thread 21 on it, which engages with the worm-wheel 22 on the lower end of the vertical shaft 19. This horizontal shaft has hand-wheels on its projecting ends, and by means of it the cars can be uncoupled from either side without going between them.

Beneath each car is secured two fixed metal air-tubes 23, which conduct the air to the air-brakes. The ends of these tubes are connected by flexible tubes 24 with the inner ends of the movable tubes 2, and permit of the movement of the latter tubes as the cars are coupled and uncoupled.

Within the conical bores 4 and 7 of the castings 3 and 6 are arranged air-valves 25, which are tapering in form and of such size as to close the outer ends of the said bores. Through the center of these valves pass small rods 26, having enlarged ends 27, the valves being fixed on the rods so that the rods cannot move through them. When the cars are uncoupled, the valves are pressed outward by small spiral springs 28, assisted by the pressure of the air from within the tubes, thus instantly and automatically closing the ends of the air-tubes, as shown in Fig. 1. When the ends of the cars come together in coupling, the outer ends of the rods 26 come in contact, and thus press the air-valves back, opening the ends of the tubes when the cars are coupled, as shown in Fig. 3.

Fig. 4 shows a short form of the coupler used beneath the cab, the casting 6 being bolted, as shown, directly to the end of the cab, and the sliding tubes 2 being dispensed with.

When it occurs that two cars approach each other with their corresponding ends—viz., those ends which are provided with the clamps 12—brought together, in order to enable them to couple I employ a device consisting of the heavy plate 29, formed with two projecting hollow cones 30, which is clamped on the end of one of the castings 6. This will give that casting an outer end which

substantially corresponds to the shape of the casting 3, so that the clamps of the casting 6 on the other car can engage with the extended ends of the plate 29, while the other clamps pass outside of these engaging-clamps, as shown in Fig. 7 of the drawings.

Having thus described my invention, what I claim, and desire to secure by Letters Patent, is—

1. The combination, in a combined automatic car-coupler and air-brake, with the fixed air-pipes 23, of the tubes 2, movably supported in bearings, the flexible tubes connecting the rear ends of said movable tubes with the ends of the fixed pipes 23, the casting 3, bolted to the outer end of the movable tubes 2 and formed with the outer wings 5 and the tapering bores 4, the casting 6, bolted to the outer end of the movable tubes 2 and formed with the tapering bores 7, and the outer end shaped to receive the outer end of the casting 3, the draw-bolts 14, secured to the movable tubes 2 and having the bumper-springs, the spring-actuated clamps 12, pivoted on the cross-bar 11 of the casting 6, the conical spring-actuated air-valves 25, sliding in the bores of the castings, the rods 26, passing through the air-valves and secured thereto and having the enlarged ends, and the shafts connected to the rear ends of the clamps 12 for uncoupling from the top or sides of the cars, substantially as set forth.

2. The combination, with the castings 6, having the conically-recessed outer ends, and the pivoted clamps 12, of the plate 29, adapted to be secured to the outer end of one of said castings, having the hollow cones 30, and formed with the extended ends, substantially as set forth.

In testimony whereof I affix my signature in presence of two witnesses.

JOHN C. F. RIPLEY.
